UNITED STATES PATENT OFFICE.

RALPH L. GREENE, OF ATTLEBORO, MASSACHUSETTS, ASSIGNOR TO SHAMBOW SHUTTLE COMPANY, OF WOONSOCKET, RHODE ISLAND, A CORPORATION OF RHODE ISLAND.

SHUTTLE.

Application filed July 21, 1924. Serial No. 727,141.

To all whom it may concern:

Be it known that I, RALPH L. GREENE, a citizen of the United States, residing at Attleboro, in the county of Bristol and 5 State of Massachusetts, have invented certain new and useful Improvements in Shuttles; and I do hereby declare the following to be a full, clear, and exact description of the invention, such as will enable others 10 skilled in the art to which it appertains to make and use the same.

The present invention relates to an improvement in shuttles, and more particularly to the springs used in weft replenishing loom shuttles.

The object of the invention is to reorganize and improve shuttles with respect to the support of the springs in the shuttle body. To the above end the present invention consists 20 in the shuttle hereinafter described and particularly defined in the claim.

In the accompanying drawings illustrating the preferred form of the invention, Fig. 1 is a plan of a portion of a shuttle 25 for a loom of the bobbin changing type, illustrating the spring construction; Fig. 2 is a sectional elevation of the same; and Fig. 3 is a horizontal section taken on the line 3—3 of Fig. 2.

30 The illustrated embodiment of the invention is described as follows: The shuttle body 10 has the usual bobbin receiving recess 11. The shuttle spring 12 is of the usual form, having arms 13 adapted to engage the opposite sides of the butt of the bobbin. The shuttle spring is of the usual form, having a U-shaped portion 14 which unites the ends of the arms embracing a spacing piece 15, through which U-shaped 35 portion and spacing piece the bolt 16 passes to secure it in place in the shuttle body. The shuttle is provided with the usual bobbin guide 17, which consists of a piece of metal having an inclined portion which 40 serves when the bobbin strikes it to guide the bobbin butt down and to move it longitudinally of the shuttle so as to bring it into proper position to be forced between the arms 13 of the spring. Integral with the bobbin guide is the bottom plate 18 which is received in a groove in the body of the shuttle and extends under both arms rearwardly, tapering until it reaches the corners 19 of the recess in the

shuttle body, then extending on in parallel 55 lines to a point beyond the end of the double portion of the spring, as shown in dotted lines in Fig. 3. This bottom plate is of the usual construction. A filler plate 21 is provided which is received in a groove cut 60 in the body of the shuttle, which has two arms extending outwardly on top of the arms of the spring, and a body portion which extends rearwardly into a slot cut in the shuttle body, as shown in full lines in Fig. 65 3. The top plate of the bobbin guide is a horizontal strip of metal 22, which extends rearwardly from the top of the inclined portion over the upper surface of the filler plate, being received in a recess cut in the 70 shuttle body and having its ends secured in place by a wood screw 23. The top plate of the bobbin guide is of the usual construction. The filler plate is provided with a rectangular recess 24 which receives the 75 upper end of the inclined portion of the bobbin guide, as shown in Fig. 3. The length of the recess is equal to the width of the inclined portion of the bobbin guide, and the filler plate and bobbin guide are 80 thereby interlocked.

When a transfer takes place in a weft replenishing loom employing shuttles of this type, the butt of the bobbin is designed to enter between the ends of the arms of the 85 shuttle spring, and as it enters to force out ahead of it the exhausted bobbin. It sometimes happens that the shuttle is not quite correctly positioned in the shuttle box to receive the incoming bobbin. The design is 90 such that an error in the positioning of the shuttle in the shuttle box under the hopper will never be too far to the left, as viewed in the drawings. If the shuttle should come to rest in a position too far to the left, the 95 transfer would be arrested by the shuttle feeler mechanism, so that errors in positioning the shuttle are always on one side, that is to say, always such that the shuttle is slightly too far in the shuttle box, as a result of which when the transfer takes place, the butt of the bobbin strikes the incline of the bobbin guide and moves the shuttle to the left, (or it sometimes happens that it 100 is itself moved to the right,) so as to bring the butt of the bobbin into register with the ends of the shuttle spring arms. This blow of the bobbin on the shuttle springs 105

and bobbin guide racks the connection between the arms and the shuttle. Sometimes it tends to move the spring bodily to one side or the other, and this tendency in turn is transmitted to the bobbin guide. Heretofore the filler plate has been more or less free to move laterally by driving its edges into the body of the shuttle, and this movement sometimes becomes so great as to cause one or the other of the horns of the filler plate to impede the entrance of the bobbin into the shuttle. By interlocking the filler plate and bobbin guide together, the vibrations and strains on the shuttle spring and bobbin guide are distributed over larger surfaces, and the guide and filler plate are

thereby more securely held in position in the shuttle.

Having thus described the invention, what is claimed is:

A shuttle comprising a body provided with a bobbin recess, a shuttle spring and bobbin guide supported in the shuttle body, and a filler plate provided with a recess adapted to embrace the inclined portion of the bobbin guide so as to interlock the bobbin guide and filler plate and prevent the lateral displacement of the one with relation to the other.

In testimony whereof I have signed my name to this specification.

RALPH L. GREENE.
